CLAIM

The ornamental design for a long gun case, as shown and described.

DESCRIPTION

FIG. 1 is a left, front, top perspective view of the long gun case;

FIG. 2 is a right, rear, bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top view thereof; and,

FIG. 8 is a bottom view thereof.

The shade lines in the Figures show contour and not surface ornamentation.

The broken lines showing portions of the design in all figures are included for the purpose of illustrating portions of the article that do not form a part of the claimed design.

1 Claim, 8 Drawing Sheets
